UNITED STATES PATENT OFFICE.

GEORGE FREDERICK JONES, OF CHEADLE HULME, AND THOMAS LAURENCE HALE, OF BOLTON, ENGLAND, ASSIGNORS TO THE RAMSAY CONDENSING LOCOMOTIVE COMPANY LIMITED, OF GLASGOW, SCOTLAND, A BRITISH COMPANY.

EVAPORATIVE CONDENSER FOR STEAM OR OTHER VAPORS.

Application filed December 29, 1923. Serial No. 683,376.

To all whom it may concern:

Be it known that we, GEORGE FREDERICK JONES and THOMAS LAURENCE HALE, both subjects of the King of England, and residents, respectively, of Cheadle Hulme, Cheshire, England, and Bolton, Lancashire, England, have invented certain new and useful Improvements in Evaporative Condensers for Steam or Other Vapors, of which the following is a specification.

This invention is for improvements in or relating to evaporative condensers, and has for its object to provide an improved construction of condenser of the general type described in the prior British patent specification of Ramsay No. 5,223 of 1915. In the said specification there is described a condenser which comprises a rotatable horizontally-disposed cylindrical bank of tubes which receive the vapor to be condensed, and these tubes in their rotation are dipped into a trough of liquid. The cooling of the steam to be condensed is obtained by the evaporation of the film of liquid which adheres to the tubes after their immersion.

It has been found that the efficiency of the tubes, from a condensing point of view, is reduced whilst they are immersed in the liquid, and that the efficiency of the condenser is to a large extent dependent on the thinness of the film of water on them. It is the object of the present invention to provide a condenser in which the wetting of the tubes with a film of liquid is effected in as short a time as possible, in order that the maximum condensing effect can be obtained.

According to this invention therefore, instead of providing a trough of water in which the tubes are immersed to wet them, there is provided a liquid-spraying device so situated with respect to the bank of tubes as to provide a curtain of liquid which will wet the outer surface of the tubes in a short time as they pass through the curtain in their rotation.

Preferably the said liquid-spraying device is mounted inside the bank of tubes near the bottom thereof, and the liquid is projected downwards on to the tubes.

Other features of the invention relate to details of construction as hereinafter set forth in relation to the specific embodiment of the invention.

In the accompanying drawings—

Figure 1 shows in central sectional elevation an evaporative condenser in accordance with this invention; and

Figure 2 shows a transverse section on the line 2—2 of Figure 1.

Like reference characters indicate like parts in both the figures.

The evaporative condenser comprises an outer casing 10 which may be cylindrical or of any other convenient shape, provided at each end with bearings indicated generally by the references 11, 12. At each end of the casing there is mounted an annular header 13, 14 respectively, and a bank of tubes 15 extends between the headers; this bank of tubes is cylindrical in its general formation, and the inlet-header 14 is mounted on a suitable hollow disc-shaped casting which provides a trunnion 16 rotatable within the bearing 12. Within the rotatable trunnion 16 is a tubular member 17 which is stationary and projects beyond the end of the trunnion; this member 17 constitutes the inlet for the steam to be condensed and is formed in any suitable or convenient manner for attachment to the exhaust steam pipe or equivalent part. The outlet-header 13 is connected by a number of radial pipes 18 to a tubular shaft 19 which is rotatable in the bearing 11. Suitable openings 20 in the shaft 19 communicate with an annular space 21 in the bearing, and through it with an outlet 22 in the frame supporting the bearing, this outlet 22 constituting the means whereby the condensate is withdrawn from the condenser.

As shown most clearly in Figure 1, the hollow shaft 19 is provided with a coaxial inner wall 23 to provide a closed annular space through which the condensate is delivered to the outlet 22.

Within the aforesaid hollow shaft 19, 23, there is mounted a stationary hollow shaft 24, which is supported at its outer end in a suitable bracket 25, and extends inwards to inside the bank of tubes 15. At its inner end it is provided with lateral openings 26 to afford communication to a chamber 27 (see Figure 2) which communicates with a suitable pipe or like member 28 extending lengthwise of the bank of tubes and situated inside them and opposite the lowest point of the cylindrical bank as is

shown most clearly in Figure 2. The shaft 24 and this member 28 form part of a stationary structure which is mounted inside the bank of tubes 15. This structure is supported by a shaft 29 which extends through the hollow shaft 24 aforesaid and is continued through to the other end of the condenser, where it has a bearing in the member 16 aforesaid which provides communication with the header 14; this bearing 16 is provided with a lignum vitae bush 30 which can be effectively lubricated by means of water alone. Preferably this bush 30 is secured on the end of the shaft 29 so that if it is necessary to examine or renew it, it can be withdrawn through the hollow shaft 24 without dismantling the whole condenser. The structure furthermore comprises a conical frame-member 31 near one end of the condenser and a series of conical partitions 32 which co-operate with radial partitions or baffle-plates 33, 34, all carried on the revolving structure, which includes the bank of tubes 15, to provide a tortuous path of flow for air entering the condenser casing at the right-hand end in Figure 1 by openings 35 and passing out to atmosphere at the other end through a suitable opening 36. Radial partitions 37 are provided on the inner surface of the casing 10 in line with the partitions 34 aforesaid to provide a substantially complete partition from the inner face of the bank of tubes to the casing 10.

35 The hollow shaft 24 aforesaid is provided with lateral openings 38 at its outer end which communicate with an inlet passage 39. The inner end of this shaft is closed by an enlargement 40 on the shaft 29 so that cooling water supplied through the inlet 39 is caused to pass through the shaft 24 and chamber 27 into the tubular member 28 aforesaid. Some of this water is led out at the further end of the member 28 by a pipe connection 41 to lubricate the bearing 30 aforesaid.

50 The tubular member 28 is perforated or slotted along its lowermost surface to form a series of spraying jets, or a continuous jet, whereby cooling water supplied through the inlet 39 as aforesaid is delivered as a curtain spray on to the bank of tubes 15. The wall of the chamber 27 is also provided with a jet or jets to direct it on to the ends of the tubes 15 as shown in Figure 1.

55 In the operation of this condenser, the steam or vapor to be condensed is admitted by the pipe-member 17 to the header 14 and passes thence into the tubes 15; cooling water is pumped in through the inlet 39 and projected as above described, as a curtain spray on to the tubes 15. The structure carrying the bank of tubes is rotated in any convenient manner, as for example by 60 means of a gear drive on to a toothed rim

42 secured on the header 14, so that all the tubes are passed in turn through the curtain spray and effectively wetted. The film of water which they thereby receive absorbs heat from the steam inside the tubes and the vapor is carried away by the current of air which is circulated round the tubes in the manner above described. The condensate drains into the header 13 and is thence removed through the outlet 22. Scoops or blades may be provided inside the header 13 to lift the condensate during the rotation of the header and deliver it into the tubes 18 so that it can flow through the shaft 19 to the outlet 22. It will be seen that with this construction of condenser the air and steam flow in opposite directions through it, and the arrangement whereby the water is projected downwards on to the tubes to wet them, provides for effectively wetting all of the tubes, this effective wetting resulting from the initial velocity of the water as delivered by the jets, its tendency to fall downwards, and also to centrifugal force acting on it from the rotation of the bank of tubes. It is therefore possible effectively to coat the tubes with a thin film of water during the very short space of time in which they are passing through the curtain or spray of water, and the efficiency of the whole condenser is thereby enhanced. Any excess water which is not retained on the tubes drains to the bottom of the casing 10 and is withdrawn and recirculated by the supply pump.

What we claim as our invention and desire to secure by Letters Patent is:—

1. In an evaporative condenser the combination of a rotatable horizontally-disposed cylindrical bank of tubes to receive the vapor to be condensed, means for circulating air around the tubes, and a liquid spraying device so situated as to provide a curtain of liquid which will wet the outer surface of the tubes as they pass through the curtain in their rotation.

2. In an evaporative condenser, the combination of a rotatable horizontally-disposed cylindrical bank of tubes to receive within them the vapor to be condensed, means for circulating air around the tubes, a liquid spraying device mounted inside the bank of tubes near the bottom thereof and directed downwardly to provide a curtain of liquid which will wet the outer surface of the said tubes in a short time as they pass through the curtain in their rotation.

3. In an evaporative condenser, the combination of two headers, hollow trunnions constituting the bearings for said headers, and also constituting respectively an inlet for the vapor to be condensed and an outlet for the condensate, a cylindrical horizontally-disposed bank of tubes extending between said headers, a hollow stationary

shaft extending through the trunnion of one of said headers, a spraying device mounted inside said bank of tubes communicating with said stationary shaft, 5 means for supplying liquid to said spraying device, and means for circulating air around said tubes.

4. In an evaporative condenser, the combination of two headers, hollow trunnions 10 constituting the bearings for said headers and also constituting respectively an inlet for the vapor to be condensed and an outlet for the condensate, a cylindrical horizontally-disposed bank of tubes extending 15 between said headers, a hollow stationary shaft extending through the trunnion of one of said headers, a spraying device mounted inside said bank of tubes communicating with said stationary shaft, means 20 for supplying liquid to said spraying device, and means for circulating air in a tortuous path through said bank of tubes.

5. In an evaporative condenser, the combination of a substantially cylindrical casing, horizontally-disposed bearings at each 25 end of said casing, hollow trunnions rotatable in said bearings, headers supported by and communicating with said trunnions, a horizontally-disposed cylindrical bank of tubes extending between said headers, a water-spraying device situated inside said bank of tubes and directed on to them, a hollow shaft extending through one of said trunnions and communicating with said 30 spraying device, means for supplying water to said hollow shaft, means for supplying steam to one of said trunnions, means for withdrawing condensate from the other of said trunnions, means for supplying air around said shaft, and means for circulating air 35 through said bank of tubes.

of said headers, means for rotating said headers and tubes, means for supplying air 40 to one end of said casing, an outlet opening near the other end of said casing, and baffles to direct a flow of air repeatedly through said bank of tubes.

6. In an evaporative condenser, the combination of a casing, horizontally-disposed bearings at each end of said casing, hollow trunnions rotatable in said bearings, headers supported respectively by and communicating with each of said trunnions, means 45 for supplying steam to one of said trunnions, means for withdrawing condensate from the other of said trunnions, a stationary rod extending through one of said trunnions and supported in a bearing in the 50 other of said trunnions, a bush secured on said rod and engaging the second of said trunnions, a hollow shaft secured coaxially with the said rod, means for supplying water to the interior of said stationary shaft, 55 a spraying device supported from said rod inside said bank of tubes and directed on to them, means for supplying water from said stationary shaft to said spraying device, means for supplying water from said spraying device to the bush mounted on said rod, an air inlet opening at one end of said casing, an air outlet opening at the other end of said casing, and baffles to direct the flow of air repeatedly across said 60 tubes when passing from said inlet to said outlet.

In testimony whereof we have signed our names to this specification.

GEORGE FREDERICK JONES.

THOMAS LAURENCE HALE.
